(57) CLAIM

The ornamental design for a short sleeve shirt, as shown and described.

DESCRIPTION

FIG. 1 is a perspective view.

FIG. 2 is a front view.

FIG. 3 is a rear view.

FIG. 4 is a left side view.

FIG. 5 is a right side view.

FIG. 6 is a top view; and,

FIG. 7 is a bottom view.

The dotted line disclosure, which includes the dash-dot broken lines, the evenly spaced broken lines and the long and short broken lines, illustrate environment and portions of the short sleeve shirt and form no part of the claimed design.

1 Claim, 5 Drawing Sheets

FIG. 1

FIG. 2

FIG. 3

FIG. 4

FIG. 5

FIG. 6

FIG. 7
